UNITED STATES PATENT OFFICE.

FRANK B. WOODMAN, OF BOSTON, MASSACHUSETTS, ASSIGNOR TO AMERICAN STEAM GAUGE & VALVE MANUFACTURING COMPANY, OF BOSTON, MASSACHUSETTS, A CORPORATION OF MASSACHUSETTS.

DESIGN FOR AN INDICATING HAND OR POINTER.

50,212.

Specification for Design.

Patented Jan. 16, 1917.

Application filed June 30, 1913. Serial No. 776,701. Term of patent 14 years.

To all whom it may concern:

Be it known that I, FRANK B. WOODMAN, a citizen of the United States, residing at Boston, in the county of Suffolk and State of Massachusetts, have invented a new, original, and ornamental Design for Indicating Hands or Pointers, of which the following is a specification, reference being had to the following drawing forming a part thereof.

The drawing shows in plan view an indicating hand or pointer in which my new design is embodied.

The indicating hand or pointer comprises a head and a shank; the head being com-

posed of two diverging bars joined together at one end, and a crossbar passing from one to the other of said diverging bars in a location between their ends; and the shank being connected at one end to said crossbar and having diverging branches at its opposite end.

I claim:

The ornamental design for an indicating hand or pointer as shown and described.

FRANK B. WOODMAN.
